US0D1072871S

(12) **United States Design Patent** (10) **Patent No.:** **US D1,072,871 S**
(45) **Date of Patent:** **** Apr. 29, 2025**

(54) **WIRELESS KARAOKE MACHINE**

(71) Applicant: **Shenzhen Shiwei Industrial Co., Ltd.**,
Shenzhen (CN)

(72) Inventor: **Yanjie Qiu**, Puning (CN)

(73) Assignee: **Shenzhen Shiwei Industrial Co., Ltd.**,
Shenzhen (CN)

(**) Term: **15 Years**

(21) Appl. No.: **29/950,104**

(22) Filed: **Jul. 1, 2024**

(51) **LOC (15) Cl.** **14-01**

(57) **CLAIM**

The ornamental design for a wireless karaoke machine, as shown and described.

DESCRIPTION

FIG. 1 is a front perspective view of a wireless karaoke machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of an encircled portion of the wireless karaoke machine labeled 9 in FIG. 2.

The evenly-dashed broken lines shown in the drawings illustrate portions of the wireless karaoke machine that form no part of the claimed design. The dash-dot-dash broken lines shown in the drawings encircling portions of the wireless karaoke machine illustrated in enlargements form no part of the claimed design.

1 Claim, 9 Drawing Sheets
